UNITED STATES PATENT OFFICE.

BENGT M. W. HANSON, OF HARTFORD, CONNECTICUT.

MILLING-MACHINE.

1,177,569.

Specification of Letters Patent. Patented Mar. 28, 1916.

Application filed October 9, 1914. Serial No. 865,856.

To all whom it may concern:

Be it known that I, BENGT M. W. HANSON, a citizen of the United States, residing at Hartford, in the county of Hartford and 5 State of Connecticut, have invented certain new and useful Improvements in Milling-Machines, of which the following is a specification.

This invention relates to milling-machines.

While the improvements are of prime utility when incorporated in a milling machine, it is obvious that they can be with equal advantage, utilized in conjunction 15 with other kinds of metal working machines such for example as shapers and planers.

One of the principal objects of the invention is the provision of means of a simple and effective character by which the milling 20 tool can be caused relatively to pass free or out of contact with the work approximately at the conclusion of a cutting operation, and as a matter of preference to be maintained in such relation until a second cut is to be 25 made, by virtue of which the tool cannot mar or deface the work or surface which has been previously cut. In a milling-machine there is a tendency at the conclusion of a milling operation by the tool, when free of 30 the work, to react by resiliency, and in this event the work at time is seriously affected. By virtue of my invention, this disadvantage is eliminated.

The invention possesses other features of 35 novelty and advantage, which with the foregoing will be stated at length in the following description, wherein I will set forth in detail that one of the many different forms of embodiment of the invention which I 40 have selected for illustration in the drawings accompanying and forming part of the present specification. I do not restrict myself to this disclosure; I may depart therefrom in radical respects within the scope of 45 the invention defined by the claims following said description.

Referring to said drawings, Figures 1 and 1^a are collectively a side elevation of a milling-machine involving my invention, 50 Fig. 1^a being part of the rod represented in

Fig. 1. Fig. 2 is a detail view showing the work-carriage and the work-supporting means connected therewith, a part of the head-stock and a part of the base or bed of the machine, the rod already mentioned being in transverse section. Fig. 3 is a top plan view partly in section, of the work-supporting device and adjuncts. Figs. 4, 5 and 6 are sectional views on the lines 4-4, 5-5 and 6-6 respectively of Fig. 3. 60

Like characters refer to like parts throughout the several views of the drawings, which are on different scales.

In a machine involving, my invention there is preferably a tool and a work-carriage, means for advancing and retracting the work carriage, the tool being positioned to cut the work during the advancing movement of the carriage, and means for causing relative lateral separating movement of the 70 tool and the work approximately at the conclusion of the cutting operation; by lateral movement as will be inferred, I mean motion in a direction transverse to the cutting plane or the line of travel of the carriage. 75 As a matter of preference this separation of the tool and the work is maintained preferably positively until about the time a second cut is commenced.

The machine also comprises in its organization a work-carriage such for instance as a slide, provided with rigid bearing means, a work-supporting member, means for pressing the work-supporting member against the bearing means during the cutting operation 85 at which time it may be assumed the work carriage is being advanced, and for causing the work support to move away from the bearing means on or during the return or retractive movement of the carriage at which 90 point the tool is wholly out of contact with the work. As will be understood I do not restrict myself to any particular means for obtaining this relative lateral separation of the tool and the work, although as may be 95 understood from the statements already made, the best effects are obtained by a movement of the work as is represented in the organization shown in the drawings to which allusion has been made. I might 100

also note that the construction is such that the work is non-yieldingly and substantially held by a structure which may be virtually considered as integral.

6 With the foregoing general observations I will now describe fully the particular showing made by said drawings.

The various parts of the machine may be supported by any suitable framework; that 10 shown for the purpose comprises the base or bed 2. This bed 2 has ways for supporting a work carriage which as shown consists of a slide 3. From the upper side of and suitably fastened to the base 2 the head stock 4 rises, being provided with a slide 5 adjustable by the hand wheel 6 and furnished with the spindle 7 to which the arbor 8 of the cutter 9 can be detachably connected.

The foregoing is a concise description of 20 a milling-machine which is more or less common.

In my copending application filed October 9, 1914, Serial No. 865,855, I have shown a rotary cam such as 10 fastened to the power-driven shaft 11 and having the exterior race or camway 12 to receive the depending stud 13 of the work-carrier or reciprocating slide 3, this race or camway 12 being shaped to impart through the stud 13 a complete reciprocation to the work-carriage or slide 3 on each complete rotation of the cam roller or drum 10 and which is one of several convenient mechanisms for reciprocating a work-carrier. During the cutting or milling 30 operation the work is, of course, in its elevated position, the carriage or slide being advanced slowly during such operation. At the conclusion of a cut the work is receded or dropped and the return movement of the carriage which occurs at or subsequent to the milling or cutting operation is a rapid one, and owing to the fact that the work is dropped, the carriage or slide can be rapidly retracted or can be given a quick return 40 movement, and the cutting tool cannot mar or deface the work even though the tool be rotating, which I might note, is an important feature. As a matter of fact I am the first, so far as I know, in a milling machine 50 to drop the work free of the tool at the conclusion of a cut and return the carriage or slide at or not at an accelerated rate of speed while the cutting tool is rotating. In conjunction with said work carriage 3 there is 55 a work-supporting device of suitable construction, the two being associated in any desirable manner. A work-supporting device such as that denoted in a general way by 14 and shown in detail in Fig. 3 answers my 60 requirements. While this work-supporting device 14 might be rigid or integral with the work-carriage or slide 3, I prefer that it be adjustable thereon as will hereinafter appear. Said work-supporting device as rep-

resented comprises three principal elements 65 as 15, 16 and 17, the part 15 constituting a base, the part 16 an actuating member, and the part 17 a work-supporting member. As shown the base 15 has at opposite sides the flanges 18 and 19 disposed in parallelism and 70 between which the actuating member 16 and the work-supporting member 17 are contained. As illustrated the space between the side walls or flanges 18 and 19 is bridged by the plates 20 and 21, the two plates and two 75 flanges presenting a practically rectangular frame and being firmly secured together in some desirable manner, for instance by screws 22 extending through perforations near the ends of the plates and tapped into 80 the ends of said flanges. The side edges of the actuating member 16 and the work supporting member 17 engage at all times the inner surfaces of the two side flanges 18 and 19, the ends of the work-supporting 85 member 17 bearing against the inner surfaces of the two transverse plates 20 and 21 as shown respectively in Figs. 6 and 4. The length of the operating member 16 is less, however, than the inside distance between 90 the plates 20 and 21 to permit movement of the actuating member 16 longitudinally of the base member 15, for a purpose that will hereinafter appear.

Owing to the engagement between the 95 ends of the work-supporting member 17 and the plates 20 and 21, it will be clear that said member cannot move longitudinally as it may be raised or lowered. As shown the plates 20 and 21 are provided at their bottom with outwardly extending lugs or ears 23 slotted as at 24 to receive the bolts 25 which are adapted to enter the intermediate of the three T-slots 26 extending longitudinally of the work carriage 3, the nuts of the 100 bolts 25 when set securely clamping the work supporting device in its adjusted position. By loosening the nuts the work supporting device 14 may be adjusted longitudinally of the work carriage 3, and when the adjustment is secured said nuts will be set. While in some cases the work might be directly mounted upon the work-supporting member 17, I have not shown this condition in the 105 drawings, the work 27 being clamped or otherwise suitably connected with a fixture as 28 which in turn is conveniently connected with the work supporting member 17 as by one or more bolts 29, so that the work 27 is thus rigidly connected with the work-supporting member 17, it following that the work partakes of the motion of said element 17. As represented the actuating member 16 is interposed between the base 15 and the 110 work supporting member 17 the latter in the organization shown being capable of solely perpendicular movement with respect to the base 15, means being provided as already de-

scribed to prevent any other movement which is advantageous though not essential, as I have already intimated. The effect of the actuating member 16 can be applied to the work supporting member 17 in some suitable manner, for instance by cam or wedge means, the engaging faces of the two parts being of wedge shape and being divided into steps. By virtue of this division (two steps being shown), I can make the pitch of the wedge sufficiently steep to secure the requisite lifting power. When the wedge operating element 16 is slid to the left in Fig. 4 it follows that the work-supporting member 17 and hence the work 27 will be raised whereas when said element 16 is slid toward the right, the work-supporting member will be caused to lower the work and as a result being also lowered.

As will hereinafter appear I do not rely on gravity to effect the descent of the part 17, positive means being furnished for this purpose. When the work-supporting member 17 is in its extreme elevated position it abuts against suitable bearing means which may vary decidedly as to character, although the overhanging flanges 30 and 31 of the walls 18 and 19 respectively, answer satisfactorily in this respect, these flanges extending inward from the side walls 18 and 25 being practically coextensive therewith. The upper wedge element or work supporting member 17 has the laterally extending ledges 32 and 33 which are adapted to be impinged against these inwardly extending flanges 30 and 31 respectively approximately at or before the commencement of a cut thereby to rigidly and substantially clamp the work supporting member 17 in its elevated position, downward thrust being resisted by the wedge 16 and base 15, so that there is practically solid stock between the work-supporting member 17 and the base 15 to thereby prevent chattering or vibration.

It will be clear that said ledges 30 and 31, 45 constitute a convenient means for resisting reactive thrusts of the work during the time the latter is being milled. While in the organization shown said reactive thrusts are upward or vertical, this may not always be the case.

In the organization shown the work-supporting member 17 is elevated partly across the cutting plane at about or just before the commencement of a cut so that the last mentioned function can be obtained and is lowered at practically or after completion of a cut, so that the work is moved partly below the cutting plane, the latter relation being maintained until a second cut is to be made and slightly before this latter point the part 17 is again elevated, and this condition is continued until the second cut has been finished, it being evident that the work follows

virtually a rectangular orbital path, the work wholly clearing the teeth of the milling cutter on the backward or retractive movement of the slide. The work-supporting member 17 is shown provided with pins 34 rigid therewith and which extend freely into openings 35 in the operating member 16. As illustrated the shanks of these pins can be driven into openings 36 in the connecting surface between the steps of said work-supporting member, while the openings or counterbores 35 can be formed in the corresponding surface 37 of the actuating member 16, the free ends of said pins as shown, bearing against the upper portions of the counterbores 35 but not against the lower portions thereof. The plates 20 and 21 may be provided with practically similar pins 38 extending freely into counterbores 39 in the ends of the operating member 16, the free portions of the pins 38, however, bearing against the lower parts of the counterbores 39. This construction provides for maintaining the two parts 16 and 17 in parallel relation and also in holding the part 16 against its seat without in any wise effecting free movement back and forth of said actuating member 16. Said actuating member is shown as being in its operative position in Fig. 4 at which time there is a space or interval between the surfaces 36 and 37. By moving the part 16 to the right in Fig. 4 the work-supporting member 17 will be caused to lower the surface 37 approaching the opening 36. I do not rely upon gravity to cause the downward movement of the part 17, the latter being positively drawn down by the inclined pins 34 as the actuating member moves to the right in Fig. 4. On movement of the part 16 to the left, the companion member 17 will be elevated and the ledges or projections 32 and 33 pressed respectively against the flanges 30 and 31. From what has been noted it will be clear that in the construction shown the member 17 is elevated before the cutting or milling operation and is lowered at or after such an operation, these functions being alternately obtained by the movement of the wedge 16 with respect to the base 15 and the means shown whereby this is accomplished is quite satisfactory.

In the bottom of the operating member 16 near the forward side thereof is the chamber or cavity 40 open on one side and in which is mounted an operating-member, such as the sector 41 pivoted as by the pin 42, between its ends to the upper flat side of the base 15, the toothed portion of said sector 41 extending outwardly through the open side of said chamber 40 and its teeth being in mesh with those of the rack 43, the laterally extended portion 44 of the wall 19 having a socket 45 to slidably receive said

rack which is shiftable as will hereinafter appear with respect to the work-supporting device 14. The toe portion 46 of the relatively oscillatory sector 41 is coöperative with the stud 47 rigid with the actuating member 16, said stud 47 being situated in the chamber 40 alluded to. The heel 48 of the sector coacts with a bearing shown as adjustable and which may consist of the member 49 pivoted as at 50 to the actuating member or wedge 16 in said chamber 40. The surface of the heel 48 which engages the abutment surface 51 is preferably on an arc struck from the center of motion of the oscillatory section 40. To adjust the bearing member 49 for instance to take up wear, the screw 52 may be provided, said screw being tapped into the forward reduced portion of the bore 53 extending obliquely of the actuating member 16, it being evident that the adjusting screw 52 is also obliquely disposed. The outer end of the bore 53 is normally closed by the plug 54 by removing which access may be had to the screw 52 to effect the adjustment of the pivoted bearing member 49. The rack 43 as shown is provided with an extension in the form of a rod 55 provided with projections 56 and 57 thereon shown as adjustable collars, said rod 55 extending through the slot 58 of the actuator 59, the shank of which can be fastened suitably as by screws to the back of the head stock 4, the collars 56 and 57 being situated on opposite sides of the stationary actuator 59.

In Fig. 1 where the principal parts of the machine are shown the work carriage on its advance moves toward the right, the opposite or retractive stroke being toward the left. In Figs. 3 and 4 the actuating member 16 is shown in its operative position, having when moved to such position raised the work supporting member and hence the work 27 associated therewith. It will be understood that when the carriage 3 moves to the right the work supporting device 14 is correspondingly moved and also that in Fig. 1 the parts 16 and 17 are assumed to be occupying the positions shown in Figs. 3 and 4. Just before the work carriage 3 completes its advancing movement or at least at or about the time the cutter 9 has finished its work and about which point the work carriage 3 is to be reversed, the collar 56 will strike the actuator 59, so that on the slight further advancing movement of the carriage 3 the movement of the rod 55 will be arrested and said rod and rack 43 will be relatively speaking thrust to the left in Fig. 3, thereby causing the sector 41 to rock and the toe 46 thereof to engage the stud 47 and hence moving the wedge 16 relatively to the right in Figs. 3 and 4. As a matter of fact the movement of the wedge 16 is arrested, the movement

being a relative one as will be inferred. On such relative movement the wedge or actuating member 16 draws the work supporting member 17 downward thereby moving the work 27 away from the cutter 9. When the work is lowered or at about this time the carriage 3 is reversed and is returned to its initial position, all by the cam 10 in the manner described. Just before the work carriage 3 reaches its initial position, the work 27 being down on the return stroke, the collar 57 will strike the actuator 59 so that on the slight further retractive movement of the work carriage the collar 57 will strike the actuator 59 and thereby relatively move the rod 55 and rack 43 to the right in Fig. 3, so that the rack by acting against the bearing member 49 can relatively move the wedge 16 to the left in Figs. 3 and 4 so as to effect the elevation of the wedge 17 and the abutment of its ledges 32 and 33 against the flanges 30 and 31, this action being concluded at about the time the return movement of the work carriage 3 should commence. When the wedge 16 is moved to the left in said Figs. 3 and 4 the work supporting member 17 and the parts mounted thereon including the work 27 are elevated and the elevated relation will be maintained until the collar 56 strikes the actuator 59 at about the conclusion of the advancing movement of the work carriage 3 at which point the described operation will be repeated.

As may be inferred, the invention involves certain broad principles, one of them the movement of the work toward and from the milling cutter automatically practically before and at the conclusion of a cut respectively. In the showing made the movement of the work from the slide is upward, so that the work is caused to partially cross the cutting plane of the cutter to position the work to be milled. At the conclusion of the cut or practically thereto, the work is moved partially below the cutting plane, so that as the carriage or slide travels backward, there is no possibility of the work being injured by the cutter, notwithstanding the fact that the cutter is rotating. This is a most important consideration and so far as I am aware has never been done in a milling machine. It is a matter of great importance that the thrust of the tool against the work should be effectually resisted to eliminate chattering and hence obtain excellence of product. There are two thrusts to be resisted, and these are transverse to each other, being in the present case approximately at right angles to each other, the resultant being on a line between the other two lines of thrust. In the organization shown there is a downward thrust and a back thrust during cutting, the resultant being along a diagonal line between the horizontal and vertical

lines of thrust. Various means may be provided for resisting these thrusts during the cutting action. The slidable wedge member 16 resists the down thrust and the wall 21 5 against which the upper slidable member 17 has a constant bearing engagement resists the back thrust. Were the work carried by a pivotal support, the pivot of the said pivotal support would resist the back thrust, 10 while a slidable wedge or some equivalent element interposed between the support 17 and the slide, would resist the down thrust. While as I observe it is practically imperative that these thrusts should be resisted, I 15 do not wish to restrict myself, there being no necessity for doing so, to an organization comprising such means. By resisting the two thrusts the work will be held substantially against the cutting tool during the 20 milling operation.

What I claim is:

1. In a metal working machine the combination of a slide, means for automatically advancing and retracting the slide, a cutting tool in coöperative relation with said slide, work supporting means on the slide, the tool acting to cut the work during the advance of the slide, and means for moving the work in a direction away from the slide and sufficiently across the cutting plane of the tool before the work reaches the tool to position the work to be cut as the slide advances, for maintaining a substantially solid unbroken support between the slide and the work-carrying means to thereby form a non-yielding base or support to resist thrusts upon the work, and for moving the work away from the cutting plane after the cut has been made to free the work from the tool as the slide is 40 retracted.

2. In a metal working machine the combination of a slide, means for advancing and retracting the slide, a cutting tool in coöperative relation with said slide, work supporting means on the slide, the tool acting to cut the work during the advance of the slide, and means for moving the work in a direction away from the slide and sufficiently across the cutting plane of the tool before 50 the work reaches the tool to position the work to be cut as the slide advances, for maintaining a substantially solid unbroken support between the slide and the work-carrying means to thereby form a non-yielding base or support to resist thrusts upon the work, and for moving the work away from the cutting plane after the cut has been made to free the work from the tool as the slide is retracted, and means for resisting 55 reactive thrusts of the work.

3. In a metal working machine, the combination of a slide, a work-holder thereon, a cutting tool in operative relation to the path of said slide, means for reciprocating said

slide, means for adjusting said work-holder toward and from the cutting plane of said tool comprising a member interposed between the lower and upper surfaces of said holder and said slide respectively, and shaped to cause a edging action when moved bodily therebetween, and means for moving said mem ef bodily along a straight line on each reciprocation of the slide.

4. In a metal working machine, the combination of a slide, a work-holder thereon, a cutting tool in operative relation to the path of said slide, means for reciprocating said slide, an adjustable supporting member interposed between said slide and said work-holder having bearing surfaces coacting with the engaging surfaces of the slide and the work-holder to cause a separation or recession thereof when moved bodily therebetween, and means for automatically moving said member bodily in alternate directions on each reciprocation of the slide.

5. In a metal working machine, the combination of a reciprocatory slide, a work-holder thereon, a cutting tool in operative relation to the path of said slide, means for reciprocating said slide, and means for moving said work-holder toward and from the cutting plane of said tool comprising a member movable with the slide and having a bearing surface coöperating with a supporting portion of said work-holder to cause a cam movement therebetween, and means for bodily moving said member on said supporting portion.

6. In a machine of the class described, the combination of a work carriage, a work supporting member on the carriage, a slid- 100 able wedge for governing the work supporting member, and automatically operative mechanism for sliding said wedge to cause 105 the same to elevate the work supporting member on the advancing movement of the carriage and to effect lowering of the work supporting member on the opposite movement of said carriage.

7. In a machine of the class described, the combination of a reciprocatory carriage, a pair of engaging wedges, one of which constitutes a work supporting member, and mechanism for automatically operating the 115 other wedge at predetermined points in the advance and retraction of the carriage to raise and lower respectively the work supporting wedge.

8. In a machine of the class described, the combination of a reciprocatory carriage, a pair of engaging wedges, one of which constitutes a work supporting member, mechanism for automatically operating the other wedge at predetermined points in the ad- 125 vance and retraction of the carriage to raise and lower respectively the work supporting wedge, and fixed means, connected with the

carriage against which the work supporting wedge engages when in its elevated position.

9. In a machine of the class described, the combination of a reciprocating carriage, a base connected with the carriage, a wedge slidable on the base, said wedge having a stud and a bearing, a pivotally mounted sector, the wedge having a chamber to receive the stud and the bearing, the chamber being open and the sector projecting from the open side of the chamber, a rack, the teeth of which are in mesh with those of the sector, the rack being equipped with a rod having projections, a fixture to alternately engage the projection to effect the movement of the rod and rack and thereby opposite movements of the sector, whereby the sector will engage said stud and bearing to move said wedge in opposite directions, and a second wedge positioned to be raised and lowered by the first wedge.

10. In a machine of the class described, the combination of a work carriage provided with side walls having overhanging flanges, a member fitted between the said walls flat on its under side and wedge-shaped on its upper side, a second member wedge-shaped on its under side to engage the corresponding surface of the first member, the second member having outwardly extending ledges and the walls having inwardly extending flanges, and means for sliding the first member automatically back and forward on the base to cause the same to raise and lower the second member, the ledges of the second member when raised being impinged against said flanges.

11. In a metal working machine, the combination of a slide, a work-holder thereon, a cutting tool in operative relation to the path of said slide, means for reciprocating said slide, an adjustable wedge-shaped member carried by said slide to engage a supporting surface of said work-holder, and means for bodily moving said member to cause a relative movement between said member and supporting surfaces and thereby effect a separation or approach between the slide and the work-holder.

12. In a metal working machine, the combination of a slide, a work-holder thereon, a cutting tool, means for reciprocating said slide in operative relation to said tool, a member interposed between said slide and said work-holder, having bearing surfaces in engagement with the lower surface of said holder and with the upper surface of said slide respectively, said engaging surfaces being coöperative to cause a wedging action when relatively bodily moved, and means for moving said member to thereby advance and retract the work-holder into and out of the cutting plane of the tool.

13. In a metal working machine the combination of a slide, means for advancing and retracting the slide, work supporting means on the slide, means for causing the movement of the work away from the slide and then toward the slide and for also non-yieldingly supporting the work when in a position away from the slide, and fixed means for resisting reactive thrusts of the work during the time it is away from the slide.

14. The combination of a slidable member, a pivotally mounted gear member movable with said slidable member, a rack, the teeth of which are in mesh with those of the gear member, means on the framework for oppositely moving said rack on alternate movements of the slidable member, work supporting means on the slidable member, and means actuated by said gear member for causing opposite movements.

15. In a metal working machine the combination of a slide, means for automatically advancing and retracting the slide, a rotary milling tool in coöperative relation with said slide, work supporting means on the slide, the tool acting to mill the work during the advance of the slide, and means for moving the work in a direction away from the slide and sufficiently across the cutting plane of the tool before the work reaches the tool to thereby position the work to be milled as the slide advances, for non-yieldingly resisting thrusts applied by the tool to the work in a direction toward the slide and in a direction toward the rear of the slide during the milling operation, and for moving the work away from the cutting plane after the work has been milled to free the work of the teeth of the tool as the slide is retracted.

16. In a metal working machine, the combination of a slide, means for automatically advancing and retracting the slide, a milling tool in coöperative relation with said slide, work supporting means on the slide, the tool acting to mill the work during the advance of the slide, and means for moving the work in a direction away from the slide and sufficiently across the cutting plane of the tool before the work reaches the tool to thus position the work to be milled as the slide advances and for moving the work away from the cutting plane after the cut has been made to free the work from the teeth of the tool as the slide is retracted.

17. In a metal working machine the combination of a slide, means for advancing and retracting the slide, and means for moving the work away and toward the slide at successive points during the reciprocation thereof, and for non-yieldingly preventing opposite movements of the work when the same is in the position away from the slide.

18. In a metal working machine the combination of a slide, means for reciprocating the slide, means for moving the work away and toward the slide at successive points in the reciprocation thereof and for interposing non-yielding resistance between the work and the slide when the work is in a position away from the slide, and fixed means on the slide to resist reactive thrusts of the work 10 when the latter is in a position away from the slide.
19. In a machine of the class described, the combination of a reciprocatory slide, a pair of engaging wedges, one of which constitutes a work supporting member, and mechanism for automatically operating the other wedge at predetermined points in the reciprocation of the carriage to cause the raising and lowering of the work supporting wedge.
20. In a machine of the class described the combination of a reciprocatory slide, superimposed wedges, the outer wedge constituting a work supporting member, mechanism 25 for automatically operating the inner wedge in opposite directions at predetermined points in the reciprocation of the slide to cause the outer wedge to move away from and toward the slide, and fixed means connected with the slide and against which the work supporting wedge abuts when in a position away from the slide.
21. In a metal working machine, the combination of a slide, means for reciprocating the slide, a work supporting member on the slide, means for moving the work supporting member away from and toward the slide at predetermined points in the reciprocation of the slide and for non-yieldingly interposing resistance between the work supporting member and the slide when the work supporting member is in a position away from the slide, and fixed means on the slide to be engaged by the work supporting member when the latter is in a position away from the slide.
22. In a machine of the class described, the combination of a slide, means for reciprocating said slide, work supporting means on the slide, and means for moving the work away and then toward the slide at predetermined points in the reciprocation thereof and for non-yieldingly resisting thrusts in opposite directions applied to the work when the latter is in a position away from the slide.
23. In a metal working machine the combination of a reciprocatory slide, inner and outer engaging wedges, the outer wedge constituting a work supporting member, and mechanism for operating the inner wedge at predetermined points in the reciprocation of the slide to cause the movement of the outer wedge toward and from the slide, the inner wedge having means to engage the outer wedge to positively draw the outer wedge toward the slide.
24. In a machine of the class described the combination of a slide, work supporting means on the slide, means for automatically advancing and retracting the slide, a milling tool to mill the work on the slide on the advance thereof, the slide being provided with means for holding the work sufficiently across the cutting plane of the tool to permit the tool to mill the work on the advance of the slide, and automatic means for causing the work to approach the slide at approximately the conclusion of a cut and for also causing the work to free the teeth of the milling tool as the slide is retracted.
25. In a metal working machine the combination of a reciprocatory slide, superimposed wedges supported by the slide, the outer edge constituting the work holding means, a rocking member supported by the slide, elements on the inner wedge, means for imparting movements to the rocking member at different points in the reciprocation of the slide to cause said rocking member to alternately engage said elements to thereby effect opposite movements of the inner wedge and thus to cause movements of the outer wedge toward and from the slide.
26. In a metal working machine the combination of a reciprocatory slide, superimposed wedges supported by the slide, the outer edge constituting the work holding means, a rocking member supported by the slide, elements on the inner wedge, means for imparting movements to the rocking member at different points in the reciprocation of the slide to cause said rocking member to alternately engage said elements to thereby effect opposite movements of the inner wedge and thus to cause movements of the outer wedge toward and from the slide, one of said elements being adjustable and the slide being equipped with fixed means to be engaged by the outer wedge when the same is in a predetermined position away from the slide.
27. In a metal working machine the combination of a slide, means for advancing and retracting the slide, means for holding the work non-yieldingly in a position away from the slide and for also non-yieldingly preventing reactive movement of the work, a milling tool to mill the work on the advance of the slide, and means for causing the movement of the work automatically toward the slide approximately at the conclusion of a milling operation and for maintaining said relation a sufficient length of time to prevent the tool marring the work on the reactive stroke of the slide.
28. In a metal working machine the combination of a slide, means for advancing and

retracting the slide, a cutting tool in coöperative relation with said slide, work supporting means on the slide, the tool acting to cut the work during the advance of the 5 slide, and means for moving the work in a direction away from the slide and sufficiently across the cutting plane of the tool before the work reaches the tool to position the work to be cut as the slide advances, for 10 maintaining a substantially solid unbroken support between the slide and the work-carrying means substantially coextensive with the superficial area of the work sup-

porting surface to thereby form a non-yielding base or support to resist thrusts upon the 15 work, and for moving the work away from the cutting plane after the cut has been made to free the work from the tool as the slide is retracted.

In testimony whereof I affix my signature 20 in presence of two witnesses.

BENGT M. W. HANSON.
